(57) CLAIM

The ornamental design for a soap bar, as shown and described.

DESCRIPTION

FIG. 1 is a perspective view of the soap bar of my design; FIG. 2 is a front elevation view of the soap bar, the rear elevation view being a mirror image thereof.

FIG. 3 is a right side elevation view of the soap bar, the left side elevation view being a mirror image thereof.

FIG. 4 is a top plan view thereof; and,

FIG. 5 is a bottom plan view thereof.
